UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

VALVE-CASING FOR ELASTIC-FLUID TURBINES.

1,089,672.

Specification of Letters Patent. Patented Mar. 10, 1914.

Application filed September 11, 1912. Serial No. 719,743.

To all whom it may concern:

Be it known that I, RICHARD H. RICE, a citizen of the United States, residing at Lynn, county of Essex, State of Massachusetts, have invented certain new and useful Improvements in Valve-Casings for Elastic-Fluid Turbines, of which the following is a specification.

This invention relates to elastic fluid turbines and is an improvement upon my prior Patent No. 1,021,212, March 26, 1912. As shown in that patent, all the steam entered at the upper end of the valve casing. With very large valves or where large amounts of steam must pass, it is found to be difficult to get the best results with this construction. I have, therefore, devised the invention which forms the subject matter of the present application, in which the steam is supplied to the valve casing at two or more points along its length, so that it has quick and easy access to the several nozzles. The multiple admission of steam permits the valves and valve seats to be smaller than when all the steam had to pass through the upper valve.

In my aforesaid patent, the valve seats were formed in a conical sleeve fitted into the casing. In the present application, the valve seats are separate, but of progressively different diameters so that they nest together when piled up. They can be made in large quantities to standard sizes and kept in stock, so that casings can be built up readily for different numbers of nozzles by selecting the proper number and sizes of valve seats.

In the accompanying drawings, Figure 1 is a vertical section through my improved multiple valve and its casing. Fig. 2 is a cross section of the same on the line 2-2. Fig. 3 is a cross section on the line 3-3. Fig. 4 is an end elevation of a portion of a horizontal turbine equipped with my invention and Fig. 5 shows one of the valve seats.

The turbine illustrated is of the Curtis type and has a casing 1 in which is a shaft 2 on which are mounted the bucket wheels 3 which are located in different stages of the machine and receive steam through nozzles 4. Each nozzle or set of nozzles receives steam through its own passage 5 controlled by its individual valve 6. It is to be noted that each of these valves is hollow and in addition to functioning as such, some

of them act as conduits, means or passages to convey steam from the port to one or more passages leading to the turbine. In other words said valves serve a two fold purpose. The drawing shows one nozzle 7 provided with a constantly open passage 8, in case the turbine is used to drive a centrifugal air compressor, because by this arrangement the compressor will always be revolved even if the valves controlling all the other nozzles are closed. If this arrangement is not desired, as for instance where the turbine is driving a generator, then the passage 8 can be blocked off.

The valve casing 9 contains a plurality 70 of steam passages 5, and also a plurality of steam supply or admission ports or chambers 10; one at the lower end of the casing and the remainder higher up. The steam passages are divided into groups, and the 75 admission ports or chambers are interposed between said groups. The drawing shows six steam passages and three supply or admission ports or chambers all of which receive steam from the same inlet. Above the 80 bottom port is a group of three steam passages, then the middle admission port, then a group of two steam passages, then the upper admission port and finally the last steam passage. This arrangement is merely 85 suggestive, however, and any other arrangement deemed more desirable may be adopted.

Steam is supplied through the flanged conduit 11 which leads directly to the 90 middle admission port. Ducts 12 convey steam from the conduit to the upper and lower admission ports. With the arrangement illustrated, the steam entering by the upper and middle ports divides in each case 95 between the two adjacent steam passages while that entering by the lower port flows up to the two passages immediately above it. Of course, the steam from different ports will intermingle more or less and will 100 distribute itself in accordance with the demand, as represented by the nozzle valves which are open.

The passages and ports are defined by partitions 13 in the casing and said partitions 105 contain openings, all in axial alignment, and increasing in diameter from the lowest to the highest. Each opening is made of a predetermined size to receive a standard valve seat, which consists of a bushing 14 110

having upper and lower interior ledges 15 serving as seats for a double-seat valve 6. Each bushing extends across the steam passage below it and is provided with apertures 16 between the ledges 15 through which steam can pass into said passage. At its lower end, the bushing is let into a rabbet in the opening in the partition below: being preferably provided with a small flange 17 to engage said rabbet and fit down over the upper end of the next bushing below.

The valves 6 are of the double-seat type and are preferably annular to afford a passage for the steam to pass through them. 15 The slight difference in areas of the upper and lower seats of each valve produces a slight unbalancing effect which insures a positive seating of the valve when it closes. The valves are of progressively increasing 20 diameter from the bottom to the top of the tier, to fit the tier of valve seats. Each valve can drop down through all the valve seats above its own, so that they can be quickly assembled and removed.

25 The valve stem 18 passes axially through all the valves. Strung upon it are several sleeves 19, one for each valve, and each carrying radial wings 20 which fit easily inside of their respective valves. The lower 30 end of each wing has a lip 21 adapted to engage with and lift its valve when the stem 18 is raised. These winged lifters are so located that they pick up their valves in succession, beginning with the lowest, so that 35 steam is admitted to the nozzles in succession and shut off in reverse order.

The piston 22 of the motor which lifts the valve stem works in a cylinder 23 supported on a stool 24 mounted on the valve casing. 40 The pilot valve 25 is actuated by the floating lever 26 linked to the arm 27 of the speed governor 28. The lever 26 is pivotally supported by a lever 29, fulcrumed on a hanger 30 and connected to stem 18.

45 It is customary to actuate the motor by oil pressure and to prevent escaping oil from dropping upon the valve casing and possibly entering the same, a pan 31 is provided to catch the drip.

50 In accordance with the provisions of the patent statutes, I have described the principle of operation of my invention, together with the apparatus which I now consider to represent the best embodiment thereof; but 55 I desire to have it understood that the apparatus shown is only illustrative, and that the invention can be carried out by other means.

What I claim as new and desire to secure 60 by Letters Patent of the United States, is:—

1. The combination with a valve casing having a plurality of partitions containing openings progressively increasing in diam-

eter, of bushings fitting respective openings and each provided with seats for a double 65 valve.

2. The combination with a valve casing having a plurality of partitions containing openings progressively increasing in diameter, of bushings fitting respective openings 70 and extending from one partition to the next, interior ledges on said bushings, and apertures through the walls of said bushings between said ledges.

3. The combination with a valve casing 75 having a plurality of steam passages, of a valve for each passage, and a plurality of steam admission ports interposed between certain passages.

4. A valve casing having partitions dividing it into a tier of steam passages, admission ports interposed between certain passages, aligned openings in said partitions progressively increasing in diameter, bushings fitting said openings and having apertures into said passages, and seats for double 85 valves in said bushings.

5. A valve casing having partitions dividing it into a tier of steam passages, admission ports interposed between certain passages, 90 aligned openings in said partitions progressively increasing in diameter, bushings fitting said openings and having apertures into said passages, seats for double valves in said bushings, valves on said seats, a stem 95 passing through said valves, and radial lifters on said stem.

6. The combination with a turbine, of a valve casing containing separate steam passages for the turbine nozzles divided into 100 groups, and steam admission ports interposed between said groups and adjacent to said passages.

7. The combination of a valve casing, having a plurality of partitions with passages 105 between, valves for controlling said passages, means for actuating the valves, an inlet to the casing, ports arranged to deliver motive fluid to the passages subject to the control of the valves, and ducts connecting the inlet with all of said ports.

8. The combination of a valve casing having a plurality of partitions with passages between, valves which control said passages and also act as conduits to convey fluid to 115 other passages, means for actuating the valves in a predetermined sequence, and ports located on opposite sides of the valves for supplying fluid thereto.

In witness whereof, I have hereunto set 120 my hand this 9th day of September, 1912.

RICHARD H. RICE.
